CLIP FOR AN OPTICIAN'S DISPENSING CABINET OR THE LIKE

Anthony D. Glover, Austin, Tex.

Application January 13, 1955, Serial No. 33,968

Term of patent 14 years

(Cl. D57—1)

Fig. 3.

Figure 1 is a perspective view of a clip for optician's dispensing cabinet or the like showing my new design; the broken lines showing the spectacles are for illustrative purposes only;

Fig. 2 is a top or plan view thereof;

Fig. 3 is a front view thereof;

Fig. 4 is a side view thereof from either side as both sides are similar.

I claim:

The ornamental design for a clip for an optician's dispensing cabinet or the like, substantially as shown and described.
